CLAIM

The ornamental design for an equine equipment storage cart, as shown and described.

DESCRIPTION

FIG. 1 is a top and side perspective view of an equine equipment storage cart showing my new design;
FIG. 2 is a left side elevational view thereof, the right side elevational view being a mirror image of the shown;

FIG. 3 is a top plan view thereof;

FIG. 4 is a front elevational view thereof;

FIG. 5 is a bottom plan view thereof; and,

FIG. 6 is a rear elevational view thereof.

FIG. 1

FIG. 2

FIG. 3

FIG. 4

FIG. 5

FIG. 6
